(57) **CLAIM**

The ornamental design for collector for urine or other fluids, as shown and described.

DESCRIPTION

FIG. 1 is a front, left side, and top perspective view of a collector for urine or other fluids showing the new design; FIG. 2 is a front elevation view thereof; FIG. 3 is a left side elevation view thereof;

FIG. 4 is a top plan view thereof;

FIG. 5 is a rear elevation view thereof;

FIG. 6 is a right side elevation view thereof; and,

FIG. 7 is a bottom plan view thereof.

The broken line showing is for environmental purposes only and forms no part of the claimed design.
